DESIGN FOR A FIRE EXTINGUISHER

Alvin B. Meyer, New York, N. Y.

Application September 5, 1947, Serial No. 141,215

Term of patent 14 years

(Cl. D16—2)

To all whom it may concern:

Be it known that I, Alvin B. Meyer, a citizen of the United States, and a resident of the Borough of Manhattan, city, county and State of New York, have invented a new, original, and ornamental Design for Fire Extinguishers, of which the following is a specification, reference being had to the accompanying drawing, forming part thereof.

I claim:

The ornamental design for a fire extinguisher, as shown.

ALVIN B. MEYER.
